UNITED STATES PATENT OFFICE.

JOSEPH E. O'BRIEN, OF SPRINGFIELD, MASSACHUSETTS.

DESIGN FOR A POURING DEVICE.

55,395.

Specification for Design.

Patented June 1, 1920.

Application filed January 21, 1920. Serial No. 353,128. Term of patent 14 years.

To all whom it may concern:

Be it known that I, JOSEPH E. O'BRIEN, a citizen of the United States of America, residing at Springfield, in the county of Hampden and State of Massachusetts, have invented a new, original, and ornamental Design for a Pouring Device, of which the following is a specification, reference being had to the accompanying drawing, forming part thereof.

Figure 1 is a side elevation showing the edge of the blade.

Fig. 2 is a similar view showing the edge of the blade.

Fig. 3 is a vertical sectional view.

Fig. 4 is a bottom plan view.

Fig. 5 is a top plan view.

Referring to the accompanying drawings A designates a cup shaped body providing

a handle which is formed with openings B and C on opposite sides of the upper end thereof, while the lower end is flared outwardly and a rubber ring D is detachably secured therein. The body of the handle A is formed with longitudinal corrugations radially spaced from each other. The blade E is secured by its upper end F within the handle A and is provided with a spear point or arrow shaped head G, which projects below the handle A and this blade is shown with beveled edges. The spear point or head is connected to the upper part of the blade by a reduced neck portion.

I claim:

The ornamental design for a pouring device as shown.

JOSEPH E. O'BRIEN.
